UNITED STATES PATENT OFFICE

DONALD D. WHITACRE, OF WAYNESBURG, OHIO

BUILDING BLOCK AND WALL CONSTRUCTION

Application filed January 31, 1929. Serial No. 336,581.

This invention relates to structural building tile and wall construction, and more particularly to back-up tile blocks which, with appropriate header and stretcher courses of brick, form a composite brick and tile wall.

I am familiar with the back-up tile known as "Perfection" blocks which have been very extensively used and are described and claimed in Reissue Patent No. 17,137, November 20, 1928, of which the original Patent No. 1,456,373 issued May 22nd, 1923 on the invention of John Eisenmann. My invention constitutes a departure from the Eisenmann invention and possesses novel features having numerous advantages of which economy in material, labor and structural design is not the least.

It is among the objects of my invention to provide a back-up tile block and a composite brick and tile wall, which is lighter per square foot of wall surface than those heretofore used having the same strength and other comparable advantages. Another object is to provide a block which, when set in a composite brick and tile wall, eliminates a substantial portion of the mortar joints in the wall, and thereby greatly adds to the imperviousness of the wall to the passage of moisture. Another object is to provide a back-up tile with horizontally extending voids which, when set in the wall, has a vertical dimension substantially equal to six courses of brick. A further object is to provide back-up tile having a horizontal length substantially equal to the length of a brick and a vertical height substantially equal to twice the length of a brick. Another object is to provide a back-up tile of size, shape and weight that can be readily handled and which has a relatively light weight per square foot of wall surface to facilitate the speed with which the wall may be built.

Other objects will appear from the following description of a preferred form of my invention, reference being had to the accompanying drawing. The essential characteristics are summarized in the claims.

In the drawing, Fig. 1 is a partial vertical section of a wall constructed according to my invention; and Fig. 2 further illustrates my

novel back-up block while Figure 3 is a showing of a prior art construction.

Referring to the drawing, a wall built according to my invention comprises preferably five courses of stretcher brick 1 arranged between courses of header brick 2, which is known as the usual six course bond. Bonded between the inner ends of the header brick are back-up tile 3 having their voids extending horizontally and having half course offsets on both their upper and lower surfaces adjacent the inner ends of the header brick. The blocks 3 are spaced from each other by mortar beds 4, which beds substantially bisect the header course of brick. There are thus no continuous mortar beds extending through the wall and the only mortar bed in the tile part of the wall are the narrow beds 4, which in a "12" wall as illustrated, are only about 4" wide, or equal to about the width of a brick.

The back-up tile 3 have a length *a* measurable in the direction of their voids or in the direction of extrusion of the blocks and have a maximum vertical height *b* measurable at right angles to the direction of the voids. As mentioned above, the height *b* is substantially equal to twice the length *a* and the length *a* is cut to equal the length of a brick. In practice, I prefer that the dimension *b* equal $2a + \text{mortar thickness}$, so that two of the blocks 3 may be end-set to have the same vertical displacement as one of the blocks when side-set, as shown.

Referring to Fig. 2, the block 3 is shown to have one horizontal web 5 jointing the vertical shells of the block in the mid-portion thereof. Contrasted with this, are shown two prior art blocks P spaced apart by a mortar joint 6 lying between adjacent shells 7 and 8. The two blocks P, when placed in a wall, have the same vertical displacement as my back-up block 3 and it is to be noted that with my block and system of construction, I have eliminated the mortar joint 6, thereby saving the cost of mortar, the cost of spreading the mortar, and the weight of the mortar in the wall. The elimination of this mortar joint which, in a "12" wall, is about 8" wide, reduces the mortar in the tile part of the wall

by about 67%. It will also be appreciated that the elimination of this mortar joint substantially doubles the imperviousness of the wall to the passage of moisture.

- 5 It will also appear from Fig. 2 that the block 3 having a horizontal web 5, is substantially as strong as the two blocks P, and that the mass of the block 3 is less than the combined masses of the two blocks P by reason 10 of the elimination of substantially all of one of the shells 7 or 8. Thus a wall built of my back-up tile is lighter than a wall built of other kinds of tile, by reason of the elimination of the equivalent of one of the horizontal 15 shells of the old type of tile and the large mortar bed, mentioned above.

By extruding the block 3 with a dimension measurable at right angles to the voids substantially equal to six courses of brick, I am 20 enabled to side-set the blocks, thereby eliminating the circulation of air in the tile part of the wall and maintain a high insulating value for the wall. The blocks 3 have a surface dimension approximately 8" x 16", 25 which is substantially 33% greater than the surface dimension of the prior art, so that about one-fourth less blocks are required in a given wall, with the consequent saving of time and labor in laying the wall.

- 30 There follows from the advantages enumerated above, a wall constructed according to my invention weighs less than walls heretofore constructed, and that the reduced weight of the wall reflects a saving in the rest of the 35 structure of the building, particularly in the mass of steel in the frame and, the size and strength of the footings.

While modifications within the scope of my 40 invention may occur to those skilled in the art, and while I have illustrated and described a preferred form thereof, I do not care to be limited in the scope of my patent, other than by the claims appended hereto.

I claim:

- 45 1. A composite brick and tile wall comprising a brick facing part with a plurality of stretcher courses between header courses of brick, a tile back-up part with single courses of hollow tile blocks disposed generally 50 between the inner ends of header brick, each of said back-up blocks being side-set and having offsets formed in its upper and lower shells equal to half the thickness of a course of brick for receiving the inner end 55 of the header brick in said offsets, vertically adjacent pairs of said blocks bonding with and overlying the inner ends of header bricks and vertically adjacent courses of header bricks bonding with and overlying the inner 60 portions of said back-up blocks.
2. A composite brick and tile wall comprising a brick facing part having a plurality of stretcher courses between header courses, a tile back-up part comprising side-set blocks 65 with offsets in their upper and lower shells

for receiving the inner ends of the header bricks, the offset being equal in depth to half a course of brick, said tile blocks being spaced from each other by a mortar bed which bisects the header courses, each tile block being bonded with one header course of brick in its top shell and with another course of header brick in its bottom shell, the only mortar joint in the tile part of the wall being non-continuous and opposite the middle of the ends of the header brick.

In testimony whereof, I hereunto affix my signature.

DONALD D. WHITACRE.
